UNITED STATES PATENT OFFICE.

JOHN HEBER, OF NEW MARTINSVILLE, WEST VIRGINIA.

DOOR-CHECK.

1,169,538.

Specification of Letters Patent. Patented Jan. 25, 1916.

Application filed June 16, 1915. Serial No. 34,337.

To all whom it may concern:

Be it known that I, JOHN HEBER, a citizen of the United States of America, and resident of New Martinsville, county of Wetzel, 5 and State of West Virginia, have invented certain new and useful Improvements in Door-Checks, of which the following is a specification.

This invention relates broadly to door 10 checks, and specifically to a door check of pneumatic type.

The primary object of the invention is to provide a durable and efficient door check which is of extremely simple and comparatively inexpensive construction.

A further object is to provide a pneumatic door check composed of but few parts that are liable to become out of order, and the application of which requires no special 20 skill.

With these and other objects in view, the invention resides in the features of construction, arrangement of parts and combinations of elements which will hereinafter 25 be exemplified, reference being had to the accompanying drawings, forming a part of this specification, in which—

Figure 1 is a front elevation of the invention applied to a door; Fig. 2 is a similar elevation, enlarged, a portion of the cylinder being shown in section; Fig. 3 is a top plan view of the same; and Fig. 4 is an elevation of the adjustable relief valve.

Referring to said drawings, in which like 35 designating characters distinguish like parts throughout the several views—1 indicates a bracket of yoke shape adapted to be rigidly mounted upon a door-casing 2 at a suitable point over a door 3. Pivotaly connected to 40 said bracket, as on a pivot pin 4 directed through the outer ends of the parallel members of said bracket, are the parallel members of a yoke 5 which is rigidly mounted on the end of a hollow cylinder 6, said pivotally connected members 1 and 5 constituting a hinge connection between said cylinder 6 and the door-casing 2. Reciprocable within 45 said cylinder is a plunger or piston 7 having a rod or stem 8 projecting therefrom through the closed rear end of said cylinder. The outer end of said stem is pivotally connected, as through the intermediacy of a flexible yoke 9, to the upper end of an outwardly and upwardly curved bracket 10 50 which is stationarily mounted on the upper portion of the door 3 at a point located a

suitably spaced distance from the rear, or hinged, edge of the latter.

The parts described are so proportioned and disposed with respect to each other that 60 the piston occupies a position closely adjacent to the front end of the cylinder when the door occupies closed position, and also that said piston has sufficient travel in said cylinder to permit the door to be swung to a 65 wide-open position.

Connected to the cylinder at a suitable point, as by means of a hook 11 mounted on the cylinder, is one end of a retractile coil spring 12 the opposite end of which is suitably attached to the rear end of the rod or stem 8, as through the intermediacy of a hook 13 fixed either on said stem or on the yoke 9. As is obvious, said spring serves to normally maintain the piston in a forwardly 75 thrust position within the cylinder. Said spring is disposed substantially parallel to said cylinder and is located between the latter and the door casing, being substantially concealed by the cylinder and piston rod 80 from the view of persons facing the door.

In practice, when the door 3 is swung open, the bracket 10 is carried outward and rearward therewith, and, consequently, the rear end of the cylinder is slightly swung therewith. This outward swinging movement is permitted by the hinge connection between the cylinder and the door casing. The rearward movement of said bracket acts to draw the piston rearward in the cylinder and to 90 compress the air in the rear end of the latter, and also to place the spring under strong tension. Then, when the opened door is released, the spring assisted by the expanding air acts to rapidly swing the door toward 95 its closed position. As the door approaches its closed position, the air in the front end of the cylinder becomes compressed by the inwardly moving piston and acts as a cushion for preventing the door from closing with great force, said cushion causing a slight rebound of the door before said closing position is reached. The air so compressed gradually exhausts from the cylinder past a suitable valve provided in the cylinder and allows the door under the influence of the spring to slowly close. Said valve is preferably constituted by a screw 100 14 which is adjustably mounted in an opening 15 provided in said cylinder at or adjacent to the front end of the latter. Said screw serves both as an inlet and exhaust 110

valve, a shallow thread-intersecting groove 16 being provided therein through which air is admitted to and exhausts from said cylinder respectively with rearward and forward movements of said piston. By adjustment of said screw the rapidity at which the air is exhausted from the cylinder may be regulated.

What is claimed is:

10. The combination with a door and a door-casing, of a door check comprising a cylinder, a yoke mounted upon the front end of said cylinder and having pivotal connection with a similar yoke mounted upon the door-casing whereby is constituted a hinge connection between the cylinder and door-casing; a piston reciprocable within said cylinder, a rod extending from said piston through the rear end of said cylinder, an 15 outstanding bracket carried by said door ad-

jacent to the hinged edge thereof, a yoke pivotally connecting the outer end of said rod with said bracket, a retractile coil spring located substantially parallel to said cylinder and between the latter and the door casing so as to be partially concealed by the latter, said spring normally maintaining said piston in a forwardly thrust position in said cylinder, said spring having its ends detachably mounted, and a valve provided 20 at the front end of said cylinder for permitting air to enter and exhaust from the latter.

In testimony whereof, I affix my signature in presence of two subscribing witnesses.

JOHN HEBER.
